BACK-TO-BACK FOUNTAIN

Gerald W. Frasier, Sherman Oaks, Calif., assignor to John Drew, Gerald W. Frasier, and John O. Hruby, Jr., co-partners include Messrs. Drew, Frasier, and Hruby, both individually and collectively, doing business as Irrigation Engineering & Manufacturing Co.

Filed Nov. 25, 1968, Ser. No. 14,645

Term of patent 14 years

Int. Cl. D23—01

U.S. Cl. D23—13

FIG. 1.

FIG. 2.

FIG. 4.

FIG. 3.

FIG. 1 is a plan view of the back-to-back fountain showing my new design.

FIG. 2 is a side perspective view.

FIG. 3 is a front elevational view of one side of the design.

FIG. 4 is a side elevational view of the design.

The rear elevational view is identical in appearance to the front elevational view and the opposite side elevational view is identical in appearance to the side elevational view shown.

I claim:

The ornamental design for a back-to-back fountain, as shown and described.
